(57) **CLAIM**

The ornamental design for mouse with narrow cross band, as shown and described.

DESCRIPTION

FIG. 1 is a perspective view of a mouse with narrow cross band showing our new design;

FIG. 2 is a bottom plan view thereof;

FIG. 3 is a top plan view thereof;

FIG. 4 is a right side elevational view, the left side elevational view being a mirror image thereof;

FIG. 5 is a front elevational view thereof; and,

FIG. 6 is a rear elevational view thereof.

Phantom lining, where utilized, is for illustrative purposes only, and is not intended to limit the claimed component design to the features shown in phantom.
